UNITED STATES PATENT OFFICE.

ARTHUR FRANCIS BERRY, OF EALING, ENGLAND, ASSIGNEE TO GENERAL ELECTRIC COMPANY, A CORPORATION OF NEW YORK.

ELECTRIC HEATING DEVICE.

1,267,173.

Specification of Letters Patent.

Patented May 21, 1918.

Application filed November 28, 1916. Serial No. 133,679.

To all whom it may concern:

Be it known that I, ARTHUR FRANCIS BERRY, a subject of the King of Great Britain, residing at Ealing, county of Middlesex, England, have invented certain new and useful Improvements in Electric Heating Devices, of which the following is a specification.

My invention relates to an electric heating device and has for its object the improvement of a device of this character.

In application, Serial No. 66,453, which was filed in the U. S. Patent Office on December 13, 1915, I have disclosed an electric heating device in which the heat is produced by a current in a bare resistance wire, carried by an insulating support, the resistance wire being made of such dimensions and so mounted and arranged that when an electric current is passed therethrough to render it luminous, not only will it produce luminous and heat-radiating effects, but it will, by reason of the varying cooling effect of the ascending air currents acting upon it and the varying refrangibility of the air, also produce an effect simulating the effect produced by the combustion of fuel. In my prior application, I have shown the resistance wire or ribbon arranged to form an upwardly ascending grid-like structure, and to form with the backing on which it is mounted a passage for the air so that when the resistance element is heated, the air is caused to ascend through the passage and impinge more or less against the resistance element.

My present invention has for its object the provision of means whereby the simulating effect of combustion may be varied and controlled so as to enhance such effect, and particularly to produce an effect resembling a red flame.

Other objects of my invention will appear from the specification and will be more particularly pointed out in the claims.

My invention will best be understood by reference to the accompanying drawings, in which Figure 1 shows in front elevation a construction of heating apparatus embodying a number of electric heat radiators similar to those described in my prior application, but showing the application thereto of one feature of my present invention; Fig. 2 is a horizontal section through Fig. 1; Fig. 3 is a vertical section through Fig. 1; Fig. 4 is

a vertical section similar to Fig. 3 but showing the shields inclined to the resistance grid; Fig. 5 is a similar view but showing one or more inclined air ducts for directing air against the resistance grid; Fig. 6 is a similar view but illustrating a number of baffles secured to the backing for directing the air against the resistance unit.

Referring now to the drawings, and first to Figs. 1, 2 and 3, each radiator comprises a resistance wire or ribbon 10, wound back and forth between the notched forward edges 11 of two vertical strips 12 of insulating material, such as thin sheet mica, so as to form a light vertical open-work grid, the strips 12 being secured to the opposite edge portions of a vertical backing 13 of concave shape in horizontal section, the space 14 formed between the resistance grid and the backing serving as a vertical passage through which air can flow in contact with the rear side of the grid at the same time that air flows over the front side thereof. The ends of the resistance strip 10 may be connected to insulated terminals 15 carried by the backing 13. All of the structures disclosed up to this point is described in my prior application and no novelty is claimed therefor.

Now, for the purpose of varying and controlling what may be called for brevity, the combustion effect, the electric heat radiator is provided with means whereby the passage of air over and against different parts of the resistance rib can be varied to produce varying effects. Thus, there may be arranged behind the resistance ribs, or each of them when two or more are used, as is shown in Fig. 1, refractory material 16 as for example, sheet mica or quartz so as to shield or protect a part or parts of the rear portion of the grid to a greater or less extent from the air, and also perhaps to deflect the air or some of it from the said parts of the grid, and in this way vary the cooling action thereon of the air flowing upwardly in proximity thereto. By this means the incandescence of the resistance grid at various parts thereof can be varied and thus also the amount of heat radiated from the various parts thereof.

It will be apparent that the shield or deflector 16 may assume various forms and be variously arranged with reference to the resistance grid. For example, I have in Fig.

- 3 shown the screen parallel to the back of the resistance grid and in Fig. 4 I have shown the grid 16 inclined thereto. It will be apparent that the shield may be flat as shown in the figures, or that it may assume a curved shape, or in fact any desired form. 5
- By arranging behind and near to and parallel with the resistance grid 10, as shown in Fig. 1, an air shield 16 consisting 10 of a thin strip of sheet mica of less width and height than the width and height of the grid, and having its upper edge of wedge or ogival shape, an effect can be produced resembling a red flame that is of greater 15 height than the air shield and extends upwardly above the same, while at the sides of the grid a varying dullness is produced more or less resembling the production of smoke or smoky flame. Owing to the varying 20 movements of the air and its varying refrangibility, the flame effect is constantly changing in position, extent and depth, thereby enhancing the simulating effect of combustion. When two or more electric heat 25 radiators of the kind referred to are arranged side by side, as in Fig. 1, the air shields 16 may be differently arranged in the different radiators to produce different effects therein. 30
- Instead of using an air shield or shields such as described, or in addition thereto, means may be provided for causing air to impinge upon part or parts of the grid in different ways to produce different effects. 35
- Thus, the backing may, as shown in Fig. 5, be provided with one or more air ducts 17, inclined or otherwise, through which air can flow toward the grid. Or, as shown in Fig. 6, the backing may be provided with 40 projecting baffles 18, or otherwise be adapt-
- ed to deflect air currents against the different parts of the grid. 45
- In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by 50 other means. 55
- What I claim as new and desire to secure by Letters Patent of the United States, is,—
1. An electric heating device comprising a grid-like structure having an exposed resistance unit, means for directing air against said unit, and means for varying or controlling the flow of air against different parts of said resistance element whereby the simulating effect of combustion may be 60 varied or controlled. 65
  2. An electric heating device comprising a grid-like structure having an exposed resistance unit which forms with the support an air passage, and means associated therewith for varying or controlling the flow of air against different parts of said resistance element whereby the simulating effect of combustion may be varied or controlled. 70
  3. An electric heating device comprising a grid-like structure having an exposed resistance unit and forming an air passage adjacent the resistance unit, and means comprising a shield or shields of refractory insulating material for protecting parts of 75 said resistance element from the effect of the air. 75

In witness whereof, I have hereunto set my hand this 9th day of November, 1916.

ARTHUR FRANCIS BERRY.
